Patented Oct. 7, 1924.

UNITED STATES PATENT OFFICE.

ERIC O. SJOLANDER, OF LOS ANGELES, CALIFORNIA.

BELT RETAINER.

Application filed July 28, 1923. Serial No. 654,431.

To all whom it may concern:

Be it known that I, ERIC O. SJOLANDER, a citizen of the United States, and resident of Los Angeles, in the county of Los Angeles and State of California, have invented certain new and useful Improvements in Belt Retainers, of which the following is a specification.

My invention is a belt retainer adapted to be attached to a garment to engage with a belt for holding the belt against displacement from a desired position on the garment, and it consists in the combinations, constructions and arrangements herein described and claimed.

An object of the invention is to provide a simple and reliable belt retainer of the character described which is adapted to be detachably secured to a garment and which when in applied position will be effective to hold a belt in a desired position on the garment without interfering with the adjustment of the belt or causing injury to the garment.

A further object is to provide a belt retainer of the character described which will take up but little space when in applied position on the garment and which is adapted to cooperate with an edge portion of the garment and with a belt which is to be retained in such manner as to be almost completely hidden from view, whereby its presence on a garment is not likely to be noted.

Other objects and advantages will be apparent from the following description, considered in conjunction with the accompanying drawings, in which—

Figure 1 is a perspective view, showing a belt retainer embodying the invention in applied position on the garment in belt retaining position.

Figure 2 is a relatively enlarged perspective view showing the belt retainer,

Figure 3 is a top plan view of the belt retainer, and

Figure 4 is a perspective view of a locking lever which is comprised in the belt retainer.

A belt retainer embodying the invention in the form now preferred by me comprises a substantially U-shaped body 1 formed of a single strip of material, such as a light gauge metal, bent transversely intermediate its length to provide a pair of parallel body members or arms 2 and 3 respectively. The body member or arm 2 is provided with an integral lateral tongue 4 which is offset out-

wardly at 5 adjacent to its juncture with the body member or arm 2 so that the tongue 4 extends for the greater part of its length in spaced parallel relation to the plane of the body member or arm 2. The width of the tongue 4 preferably is nearly equal to the length of the body member or arm 2 so that the tongue 4 will be sufficiently strong for the purpose for which it is provided, which purpose will be hereinafter more particularly set out.

The body 1 is provided with fastening means whereby it may be secured to an edge portion of a garment, as for instance to the lateral edge of the overlapping flap at the front of a pair of trousers 6 so that the tongue 4 will be held in position to extend part way across a belt 7 which encircles the trousers and to engage with the outer face and the upper edge of the belt to retain the latter against upward movement on the trousers. The particular fastening means included in the embodiment of the invention which is illustrated in the accompanying drawings comprises a substantially U-shaped spring clamp 8 which interfits the body 1 so that the arms of the spring clamp are actuated because of the inherent resiliency of the material composing the spring clamp to move apart to position to engage the inner face of the arms of the body 1. The arms of the spring clamp 8 may be forced toward each other in position to clampingly engage a portion of the garment which is received therebetween and releasably held in garment clamping position by an angle lever 9 which comprises a relatively short presser arm 10 extending through an aperture 11 in the arm 2 into engagement at its free end with the adjacent or outer face of one of the arms of the spring clamp 8, the lever arm 10 being provided at its free end with a guide projection 12 engaging with a guide slot 13 in the adjacent arm of the spring clamp. The lever 9 also includes a longer arm 14 which extends substantially at right angles to the presser arm 10 and constitutes a handle which may have the free end portions thereof enlarged as indicated at 15 so that it may be conveniently grasped to effect operation of the lever. The lever 9 is releasably held against displacement from the body 1 so that the presser arm 10 will extend through the aperture 11 into engagement with the adjacent arm of the spring clamp 8 by a pair of aligned trunnions 16

which extend laterally from the side edges of the lever along a line approximately coincident with the line of juncture of the arm 10 and the arm 14 of the lever, the trunnions being received in lateral seats in the inner face of the arm 2 at the outer end of the aperture 11.

The arms of the spring clamp 8 may be provided with inwardly extending projections or tangs 17 on their inner faces for engagement with the portion of the garment which is received therebetween. The spring clamp 8 is releasably held against displacement from the body both because of the engagement of the guide projection 12 with the guide slot 13 and because of the engagement of an outwardly extending projection 18 on the outer face of the clamp arm which is remote from the lever 9 with a recess in the inner face of the arm 3.

From the foregoing description of the various parts of the device, the operation thereof may be readily understood. It will be manifest that the body 1 will be firmly secured to an edge of a garment which is embraced by the spring clamp 8 interfitting the body 1 when the lever 9 is in the position shown in Figures 1 and 2. When the lever handle 14 is swung outward to the position shown in Figure 3, the arms of the spring clamp 8 will spring apart so that the body 1 may be detached from the garment. When the body 1 has been secured on the lateral edge portion of the overlapping flap at the front of a pair of trousers in the position shown in Figure 1, the belt engaging tongue 4 will depend downwardly from the body in overlying relation to the adjacent portion of the belt 7 which encircles the trousers and will hold the belt against upward movement at the front of the trousers and thus will hold the belt against displacement from the trousers at the front of the latter, thereby insuring that the trousers will be properly supported without there being any necessity of tightening the belt to an extent which might cause discomfort to the wearer.

Obviously, my invention is susceptible of

embodiment in forms other than that illustrated in the accompanying drawing and I therefore consider as my own all modifications and adaptations of the form of the device herein described which fairly fall within the scope of the appended claims.

I claim:—

1. A device of the character described comprising a substantially U-shaped body having a pair of spaced apart arms adapted to straddle the edge portion of a garment, a tongue integral with one of said arms and extending laterally thereof, said tongue being offset outwardly from a line adjacent to its line of juncture with said arm, and fastening means carried by the body for detachably securing the latter to the edge portion of said garment.

2. A device of the character described comprising a substantially U-shaped body having a pair of spaced apart arms adapted to straddle the edge portion of a garment, a tongue integral with one of said arms and extending laterally thereof, said tongue being offset outwardly from a line adjacent to its line of juncture with said arm, fastening means carried by the body for detachably securing the latter to the edge portion of said garment, said fastening means comprising a substantially U-shaped spring clamp interfitting said body and having arms urged continuously apart to engage with the inner faces of the arms of said body, and an angle lever carried by the tongue carrying arm of the body and having a portion extending through an aperture in said tongue carrying arm into engagement with the adjacent arm of the spring clamp, said lever being operable to effect inward movement of the adjacent arm of the spring clamp toward the other arm of the spring clamp or to permit outward movement of the adjacent arm of the spring clamp, at will, said adjacent arm of the spring clamp having a longitudinal slot therein and said angle lever having a guide projection at its inner end working in said slot.

ERIC O. SJOLANDER.
